CLAIM

The ornamental design for a decorative structural connector, as shown and described.

DESCRIPTION

FIG. 1 is a perspective view of a decorative structural connector;

FIG. 2 is a top plan view of the decorative structural connector shown in FIG. 1;

FIG. 3 is a right side elevation view of the decorative structural connector shown in FIG. 1, the left side elevation view is a mirror image thereof; and,

FIG. 4 a front elevation view of the decorative structural connector shown in FIG. 1, the rear elevation view is a mirror image thereof.

The broken lines represent environment and form no part of the claim.
